UNITED STATES PATENT OFFICE.

MICHAEL J. DAVIS, OF CHICAGO, ILLINOIS, ASSIGNOR OF FORTY-NINE ONE-HUNDREDTHS TO PAUL JONES, OF CHICAGO, ILLINOIS.

WINDOW-CLEANING ATTACHMENT.

991,140.

Specification of Letters Patent.

Patented May 2, 1911.

Application filed December 21, 1909. Serial No. 534,366.

To all whom it may concern:

Be it known that I, MICHAEL J. DAVIS, a citizen of the United States, residing at Chicago, in the county of Cook and State 5 of Illinois, have invented certain new and useful Improvements in Window-Cleaning Attachments, of which the following is a specification.

This invention relates to a window cleaning attachment especially adapted for use on 10 surface or elevated passenger cars, and is affixed to the car body so that it remains stationary while the window is being raised or lowered, and is held in impingement 15 against the window during the movements of the latter, and acts to remove all vapor or other substance which may have collected thereon and which would obstruct the view of the motorman therethrough.

20 The objects of the present invention are, to construct a device which will be extremely cheap of construction; which will not require any complicated mechanism to operate it; which can be installed without disfiguring or changing any portion of the car body; which can be readily thrown into and 25 out of service; and which will be sufficiently rigid to withstand the rough usage to which it will be subjected, without impairing its 30 utility in any degree.

The invention consists in the features of construction and combination of parts hereinafter described and claimed.

In the drawings, Figure 1 is a vertical 35 section through a portion of the front of a car body, showing the device in operative position thereon; Fig. 2, a front elevation of the car body, with the device in position 40 thereon; Fig. 3, an enlarged detail, showing the window in closed position, in full lines, and in position to be lowered, in dotted lines, and showing in full and dotted lines the relation of the squeegee to the window when the window is in either position; Fig. 45 4, a perspective of the parts in the position shown in Fig. 2; and Fig. 5, a view similar to Fig. 3, showing the frame thrown into position to carry the squeegee out of operative position.

50 As shown in Fig. 1, the device is applied to a window 5 in the front of the car body 6. The window shown is of the construction generally employed in cars of modern type, and consists of a window sash 7 held 55 against movement by a hinged shelf or ledge

8 which impinges against the lower rail 9 thereof, the upper frame 10 of the sash resting against the upper rail 11 of the window casing. The window travels within a guide-way 12, and when lowered recedes into a 60 chamber 13 formed in the front of the car body. The construction and operation of windows of this class are so well known to every one familiar with car construction that a detailed explanation is not considered 65 essential in regard to it.

The window cleaning device, as shown, is positioned upon a ledge 14 extending out from the front of the car, and the device is composed of a squeegee member 15 formed 70 preferably of rubber, and carried by a squeegee frame 16 formed of wood or other suitable material, and having a recess in its upper edge in which the squeegee member is inserted. The lower edge of the squeegee 75 frame is rounded, and is cut away at intervals, as at 17, to receive lugs 18 formed on a plate 19 attached to the ledges 14. Extending through the lower end of the frame and through the lugs 18 is a pin 20, the 80 frame and fixed plate, when joined together, forming, in effect, a hinge, in the movable part of which the squeegee member is carried. Attached to the ledge 14, at points adjacent to the sides of the fixed plate 19, 85 are flat springs 21 which bear against pins 22 affixed in the sides of the frame. By referring to Fig. 4, it will be seen that, with the parts in the position therein shown, a spring tension will be exerted against the 90 frame in a direction to hold the squeegee member in impingement against the window, and that, with the parts as shown in Fig. 5, where the frame is folded back onto the fixed plate and away from engagement 95 with the window, the spring will exert a pressure tending to maintain it in such position. As there are a great variety of well known means for creating a spring tension which will exert itself in opposite directions 100 as the member on which it acts is thrown past its center, I do not desire in any way to limit my invention to a construction in which is employed a spring of the form shown.

105 The operation is as follows: Upon days when the climatic conditions are such as to cause a vapor to collect upon the window and obstruct the view of the motorman therethrough, he will, upon leaving the 110

barn, or at a time during the trip when it becomes necessary, throw the squeegee into the position shown in Fig. 4, and thereafter every time the window is lowered or raised 5 the squeegee member will act to remove any vapor or other objectionable substance which has accumulated thereon. The squeegee will act during both the upward and downward movements of the window, there- 10 by effectively removing all objectionable substance therefrom, and at the same time all the water which will necessarily accumulate around the squeegee member after it has been passed over the surface of the win- 15 dow will not be collected at the bottom or top of the window sash, where in either case it would be objectionable. As the squeegee strikes the upper rail of the window sash, the greater portion of the dirt 20 and water will be thrown back over the squeegee, and the portion that remains will be removed when the window is raised, and in this manner no objectionable amount of moisture will remain at the top of the window 25 and trickle down as the window is moved up, and no objectionable amount of moisture will accumulate at the bottom of the window and from there pass into the car body around the openings which exist 30 between the window casing and the window sash. It will be understood that upon days when it is not necessary to use the cleaning device the frame may be thrown back into the position shown in Fig. 5, and 35 the squeegee member retracted from operative position with the window.

When in either operative or non-operative position, the window cleaning device will not interfere in any way with the usual op- 40 eration of the window, and as during the trip the motorman must necessarily often lower and raise the window for the purpose of throwing switches, etc., in the majority of cases no unnecessary movement of the 45 window will be required to keep it free from vapor or other objectionable substance.

When the device is thrown into operative position, it will lie so as to form a weather strip for the lower sash of the window, pre- 50 venting rain, snow, or wind from penetrat- ing therethrough.

When the device is applied to certain forms of windows, it will be found that the movement of the squeegee in toward the 55 window will be sufficient so that the end of the frame will extend far enough beyond its pivotal point that the pressure upon the squeegee incident to the downward motion of the window will maintain the squeegee

member in engagement with the window; 60 and in this case the spring described in the construction would, of course, not be necessary.

I claim:

1. In a window cleaning attachment, the 65 combination of a squeegee, comprising a squeegee member carried by a squeegee frame, the frame remaining in fixed position with respect to the movements of the window, and a mounting for the squeegee 70 consisting solely of a single fixed plate in which the squeegee frame is pivotally secured, substantially as described.

2. In a window cleaning attachment, the 75 combination of a squeegee, comprising a squeegee member carried by a squeegee frame, the frame remaining in fixed position with respect to the movements of the window, a fixed plate in which the squeegee 80 frame is mounted, and means for holding the frame into and out of operative position with the window, consisting wholly of a tension member, substantially as described.

3. In a window cleaning attachment, the 85 combination of a squeegee, comprising a squeegee member carried by a squeegee frame, the frame remaining in fixed position with respect to the movements of the window, and a mounting for the squeegee 90 frame consisting solely of a plate extending across and affixed to the window ledge, in which the squeegee frame is pivotally secured, substantially as described.

4. In a window cleaning attachment, the 95 combination of a squeegee, comprising a squeegee member carried by a squeegee frame, the frame being in the form of a hinge, and consisting solely of two leaves one leaf being attached to the window cas- 100 ing and the other leaf lying free and carrying the squeegee member, substantially as described.

5. In a window cleaning attachment, the 105 combination of a squeegee, comprising a squeegee member carried by a squeegee frame, the frame being in the form of a hinge, having one leaf attached to the window casing and the other leaf lying free and carrying the squeegee member, and a tension member bearing against the free 110 leaf and serving to maintain the leaves in distended or folded position, substantially as described.

MICHAEL J. DAVIS.
